HEAT TRANSFER DEVICE WITH CAPILLARY CONDENSATE DRAIN

Alvin O. Brothers, Evansville, Ind., assignor to Servel, Inc., New York, N. Y., a corporation of Delaware

Application July 1, 1944, Serial No. 543,088

13 Claims. (Cl. 62—103)

1

My invention relates to heat transfer fins and more particularly to self-draining heat transfer fins for use on a high temperature evaporator in the food storage compartment of a domestic refrigerator.

In domestic refrigerators, particularly in the food storage compartment equipped with a high temperature evaporator, the air circulating through the compartment and over and through the evaporator and heat transfer fins deposits moisture thereon which is condensed. This condensed moisture accumulates and in time trickles down over the surface of the fins and drips off the lower edges thereof. Heretofore, drip pans have been provided under the entire evaporator in order to catch this condensed moisture and prevent it from falling on to the food in the storage compartment. However, this arrangement has not proven entirely satisfactory because it interferes with the free circulation of air through the heat exchange fins and thereby lowers the efficiency of the refrigerator.

It is an object of my invention to provide self-draining heat transfer fins which drain condensed moisture away from the fins without interfering with the free circulation of air through the food storage compartment and over the heat exchange fins.

These and other objects of my invention will become more apparent when considered in connection with the following description and accompanying drawing which forms a part of this specification and wherein:

Fig. 1 is a partial perspective view of a refrigerator cabinet, showing my improved heat transfer fins attached to the high temperature evaporator located therein;

Fig. 2 is a side view, partly in section, of one form of my improved heat transfer fins;

Fig. 3 is a side view similar to Fig. 2 illustrating a second embodiment of my invention;

Fig. 4 is a side view similar to Fig. 2 illustrating a third embodiment of my invention;

Fig. 5 is a sectional view taken on line 5—5 of Fig. 2;

Fig. 6 is a sectional view taken on line 6—6 of Fig. 3;

Fig. 7 is a sectional view taken on line 7—7 of Fig. 4; and

Fig. 8 is a partial sectional view of a fourth embodiment of my improved fin.

Referring now to Fig. 1, 10 designates generally the food storage compartment of a domestic refrigerator provided with a high temperature evaporator 11 equipped with self-draining fins 12. 13

2

is a drain trough which is located directly under the rear lower edges of the fins 12 and is used to convey condensed moisture from said fins into a receptacle 14.

Referring now to Figs. 2 and 5 wherein one embodiment of my invention is illustrated, the heat transfer fin 12 is formed of flat sheet metal with sleeves 15 extending from the mid-longitudinal portion thereof. These sleeves 15 are adapted to fit around the evaporator conduit 16 in intimate heat transfer relation and may be welded or otherwise secured thereto. A U-shaped trough 17 is attached to the lower portion of the fin 12 in any conventional manner as by welding, soldering or the like, and provides capillary passages 18 and 19 on opposite sides of said fin. This trough 17 is provided with a plurality of spaced capillary openings 20 along the lower edge thereof. After these fins have been assembled on conduits 16 a strip of wire screen 21 of relatively close mesh is attached as by welding, soldering or the like, along the lower portion of the rear vertical edges of the fins, as shown in Fig. 2. This strip of wire screen extends from one fin to the next across the length of the evaporator.

In the operation of the embodiment of my invention illustrated in Figs. 2 and 5, condensed moisture that accumulates on the fins 12 trickles down over each of the faces thereof and is picked up by the capillary passages 18 and 19 which convey said moisture to the lower right corner of the fin, as viewed in Fig. 2 and from there the condensed moisture is picked up by the wire screen 21 which conveys it to the trough 13. Any condensed moisture that accumulates on the outside of the U-shaped trough 17 flows to the lower portion of said trough and passes through capillary openings 20 into the trough.

Referring now to Figs. 3 and 6 wherein a second embodiment of my invention is illustrated, numeral 22 designates a heat transfer fin generally similar to the fin 12 illustrated in Fig. 2, except that here the bottom portion of the fin is bent in such manner as to provide capillary channels 23 and 24, which collect the moisture condensed on the opposite faces of said fin. In the operation of this embodiment of my invention, the condensed moisture as it accumulates on the faces of the fin gradually trickles downwardly across said faces and into the capillary channels which convey it to the trough 13.

Referring now to Figs. 4 and 7, wherein a third embodiment of my invention is illustrated, numeral 25 designates a heat transfer fin generally similar to the fin 12 illustrated in Fig. 2, except

that here the fin 25 is provided with a U-shaped member 26 formed of relatively close mesh wire screen which extends longitudinally along the lower margins of said fin and under the bottom edge thereof. This fin operates in substantially the same manner as fins 12 and 22 described above in that moisture that is condensed thereon is picked up by the wire screen and by capillary action is conveyed to the drain trough 13.

Referring now to Fig. 8, wherein a fourth embodiment of my invention is illustrated, the heat transfer fin 27 is generally similar to the fin 12 illustrated in Figs. 2 and 5, except that here instead of a U-shaped trough the lower portion of the fin is provided with a flat strip of metal 28 on each side thereof and spaced therefrom to form capillary passages 29, 30 along the lower margins of the fin. Strips 28 may be attached to the fin in any conventional manner as by welding, soldering or the like. Here again, condensed moisture that accumulates upon the fin 27 is picked up by the capillary passages 29 and 30 and is conveyed to a common trough.

As shown in Figs. 1, 2, 3 and 4, my improved heat transfer fins are arranged on the evaporator so that the lower longitudinal edges thereof are slightly inclined downward from the front to the rear of the evaporator.

While I have illustrated and described four specific embodiments of my invention and have mentioned only one particular use for it, it is obvious that it may take other forms and that it has other uses. My improved self-draining heat transfer fins may, for example, be used with any heat exchange device wherein moisture is apt to accumulate on the heat transfer fins and wherein some means must be provided for disposing of said moisture. Therefore, my invention is to be limited only by the following claims.

I claim:

1. A self-draining heat transfer fin comprising a relatively flat member provided with capillary passages along the lower margins thereof for conveying condensed moisture therefrom.

2. In an evaporator, a conduit provided with a plurality of heat transfer fins, each of said fins comprising a relatively flat sheet metal member forming at least two heat transfer surfaces and provided with means forming capillary passages along a portion of each of said surfaces for draining accumulated moisture therefrom.

3. In a heat transfer device, a conduit for flow of heat transfer medium therethrough, a plurality of vertically disposed heat transfer fins connected to said conduit, and each of said heat transfer fins being provided with means forming capillary passages along lower margins thereof.

4. In a food storage compartment, a refrigerant evaporator provided with heat transfer fins arranged for free circulation of air thereover, each of said fins including vertically extending portions upon which moisture from said air may condense and accumulate, and means on the lower edges of said vertically extending portions forming capillary passages for conveying condensed moisture from said fins.

5. In a refrigerator, an evaporator provided with a plurality of heat transfer fins, each of said fins comprising a substantially vertical sheet metal member having capillary passages formed on the lower margins thereof, and a trough lo-

cated below said heat transfer fins at one end of said capillary passages.

6. A heat transfer fin comprising a sheet of metal, and a plurality of strips of metal connected to said sheet of metal along one edge thereof and cooperating therewith to provide a plurality of capillary passages.

7. A heat transfer fin comprising a sheet of metal, and an element U-shaped in cross-section extending along one edge thereof and cooperating therewith to provide a plurality of capillary passages.

8. In a heat exchange device, a conduit for flow of heat exchange medium therethrough, a plurality of heat exchange fins connected to said conduit, each of said heat exchange fins comprising a vertically disposed sheet of heat conducting material, and an element U-shaped in cross-section extending over one edge of said sheet and cooperating therewith to provide a plurality of capillary passages.

9. A heat transfer fin comprising a sheet of metal, an element U-shaped in cross-section extending along one edge thereof and cooperating therewith to provide a plurality of capillary passages, and said U-shaped element being provided with a plurality of capillary openings in the lower portion thereof.

10. In a heat exchange device, a conduit for flow of heat exchange medium therethrough, a plurality of rectangular vertically disposed heat exchange fins connected to said conduit, each of said fins being provided with structure along a lower edge thereof forming capillary passages, and connecting means between said fins along another edge thereof forming additional capillary passages.

11. A heat transfer fin comprising a sheet of metal having one margin thereof bent in the form of a plurality of reverse curves to provide a plurality of capillary channels.

12. In a heat exchange device, a conduit for flow of heat exchange medium therethrough, a plurality of heat exchange fins connected to said conduit, each of said fins comprising a vertically disposed sheet of heat conducting material, a portion of the margin thereof being bent in the form of a plurality of reverse curves to provide a plurality of capillary channels.

13. A heat transfer fin comprising a vertically disposed sheet of metal, and a strip of wire screen attached to the lower edge of said sheet of metal and cooperating therewith to provide a plurality of capillary passages for conveying condensed moisture from the lower edge of the fin.
